UNITED STATES PATENT OFFICE.

JOHN BOGENBERGER, OF MILWAUKEE, WISCONSIN.

METALLIC FIREPROOF WINDOW.

SPECIFICATION forming part of Letters Patent No. 788,878, dated May 2, 1905.

Application filed December 26, 1903. Serial No. 186,661.

To all whom it may concern:

Be it known that I, JOHN BOGENBERGER, residing at Milwaukee, in the county of Milwaukee and State of Wisconsin, have invented 5 a new and useful Improvement in Metallic Fireproof Windows, of which the following is a description, reference being had to the accompanying drawings, which are a part of this specification.

10 My invention relates to certain new and useful improvements in metallic fireproof windows, and more particularly to that type of window in which a swinging sash is employed.

The object of this invention is to produce 15 a tubular sheet-metal frame thoroughly braced throughout and capable of making practical weather-tight connections with its swinging sash.

A further object of this invention is to employ 20 an improved form of pivotal connection for a swinging window, permitting the window to be readily adjusted with relation to its pivotal bearing and enabling it to be quickly and easily removed from its mounting.

25 With the above and other objects in view the invention consists of the devices and parts or their equivalents, as hereinafter set forth.

Referring to the accompanying drawings, in which like characters of reference indicate 30 the same parts in the several views, Figure 1 is a vertical section of a window embodying my invention. Fig. 2 is a horizontal section of one side thereof, taken on the line 2 2 of Fig. 1 above the pivot. Fig. 3 is a similar 35 view on the line 3 3 of Fig. 1, taken through the pivotal connection. Fig. 4 is a vertical section through one of the pivotal bearings. Fig. 5 is an end elevation of the pivot-pin, and Fig. 6 is a horizontal section of one side 40 of the window on the line 6 6 of Fig. 1.

In the drawings the window-frame is shown as comprising vertical side casings 8, the top casing 9, and the sill 10, all being made of sheet metal bent in tubular form. The side 45 casings 8 are formed with angular shell members bent to form a projecting sash-bearing 11, with a shoulder 12 on the outside and a corresponding shoulder 13 on the inside, said shell member being secured at its edges by 50 slip-joints to a back plate 14, provided with

a deep central crease, in which is seated a core-plate 15, extending across the tubular structure and riveted to the shell at the sash-bearing 11. The core-plate 15 is also riveted in the crease of the back plate 14, and thus ties the shell and back plate together, besides bracing and strengthening the tubular structure. The crease of the back plate stands out therefrom as a flange to firmly anchor the frame in the surrounding brickwork or masonry. 60

The top casing 9 is formed of a single piece of sheet metal bent to form a tubular body riveted together, with the shoulder 13' and a sash-stop 16, having the inclined bearing-surface and the depending outer bent flange 17, in the crease of which is seated a core-plate 18, which extends across the tubular top casing and is riveted to the top thereof. 65

The sill 10 is bent up from a single piece 70 of sheet metal, with inclined top and bottom surfaces and an upwardly - extending glass seat 19, with an inner bent-over flange 20, holding in its crease a core-plate 21, which is riveted to the bottom of the sill. 75

A cross-rail 22 extends across the frame from one side casing to the other and is tubular, being bent to form the glass-seat 23, with the shoulder 24 on the inner side thereof, and the inclined upper sash-stop surface with the 80 upwardly-projecting inner flange 25.

A flanged U-shaped strip of metal 26 is mounted on the sash-bearings 11 between the sill 10 and the cross-rail 22 and is bent at its middle portion to form a pair of parallel glass-holding flanges 27 and has its side edges bent around and bolted or riveted to the shoulders 12 and 13, respectively. 85

A window-light 28, preferably of wire-glass, is mounted on the glass-seats 19 and 23 against flange 20 and shoulder 24 and between flanges 27 and is held in place by cleats 29, which are strips of sheet metal bent double at the middle portion, with their side edges bent away from each other to form a T shape in cross-section, the one edge being placed between the edge of the glass and the glass-seat and the other edge bent slightly out of alinement with the first-named edge to bear tightly 95 against the glass-seat. 100

A swinging window-sash is fitted in the upper part of the window-casing and comprises a tubular frame having side stiles formed of U-shaped shells 30, with glass-grooves 31 at 5 their bends and their edges turned inwardly and folded back upon themselves to form slip-joints, with the outwardly-turned edges of a bearing-plate 32 and top and bottom rails bent to form glass-seats 33, with shoulders 34 on 10 one side thereof. The outer bearing-surfaces of the top and bottom rails are inclined to fit the inclined sash-stops 16 and 22, respectively, and the top rail is provided with a weather-flange 35 at its inner edge to fit against the 15 shoulder 13, while the bottom rail is provided with a weather-flange 35 at its outer edge to fit against the outer side of the cross-rail 22. Window-lights 28 are also seated in the glass-seats 33 and grooves 31 by means of cleats 29 20 in the usual manner by employing a mullion 36 of ordinary construction.

The swinging sash is mounted on pivots in the following manner: An angular bracket-plate 37, having in its bracket or outstanding 25 member a vertical slot 38, is secured at its other member to the inner face of each of the side stiles of the sash by screws 39 threading into a back plate 40, which is fastened within the stiles by bolts 41. Likewise a socket-plate 42 is secured to the face of each side casing by screws 43 threading into a back plate 44, which is fastened within said casing by bolts 45, and at its middle portion the socket-plate is enlarged, forming a boss which is 30 drilled to produce a socket 46. A pivot-pin 47 has at its medial portion a pair of oppositely-projecting arms 48, which may easily pass through the slot 38 to enable the rounded end of the pivot-pin being seated in the 35 socket 46; but when the pivot-pin is turned a quarter-turn the arms bear against the side of the angular plate 37, so that a nut 49 when turned on the threaded inner end of the pivot-pin rigidly clamps said pin to the bracket 40 member of plate 37. It is possible with this 45 construction to adjust the sash in its frame until the desired fit is secured at all parts and then clamp the pivot-pins to maintain that relation.

50 The slip-joints between the shells 30 and the bearing-plates 32 of the sash-stiles form projecting outer flanges 50 and inner flanges 51 on each side of the sash, said flanges being split at the pivot parts. Above the pivots the 55 outer flange 50 is bent back against the bearing-plate 32 and the inner flange 51 bears against the shoulder 13, while below the pivots the outer flange 50 bears against the shoulder 12 and the inner flange 51 is bent back 60 against the bearing-plate 32, so that when the sash is in its closed position these flanges produce, with the shoulders 12 and 13, weather-tight joints the full length of the sash, and the arrangement is such that the swinging of 65 the sash is not interfered with. At the ends

of the sash the inclined sash-bearings and the flanges 17, 25, and 35 complete the weather-tight connections. Whenever further adjustment of the sash becomes necessary, it may be readily accomplished by loosening the nuts 49 70 and adjusting the sash to the desired position and then clamping the nuts again in their new positions on the slotted angle-plates 37. When the sash is desired to be removed, the pivot-pins 47 are turned while the nuts 49 are loose, 75 so that the arms 48 may be drawn through the slots 38, when the sash is free to be withdrawn.

From the foregoing it is apparent that a window made in accordance with my invention will be thoroughly fireproof and when the upper sash is closed the entire structure is perfectly weather-tight.

What I claim as my invention is—

1. In a device of the character described, a sheet-metal frame having side casings with sash-bearings, a sash pivoted to the side casings, a pair of flanges on the bearing-surface of the sash-stiles, and a shoulder along each edge of the sash-bearings, one of the flanges 90 of each sash-stile being bent over above the pivot and the other of said flanges being bent over beneath the pivot, the remaining outstanding portions of said flanges engaging with the shoulders of the sash-bearing whereby weather-tight joints are produced on opposite sides of the sash-stiles above and below the pivots.

2. In a device of the character described, a sheet-metal frame having side casings with sash-bearings, a sheet-metal sash pivoted to the side casings and comprising side stiles formed of a shell with a bearing-plate joined thereto at the edges forming projecting slip-joint flanges, a shoulder along each edge of the sash-bearings, one of the flanges of each sash-stile being bent over above the pivot and the other of said flanges being bent over beneath the pivot, the remaining outstanding portions of said flanges engaging with the shoulders of the sash-bearings whereby weather-tight joints are produced on opposite sides of the sash-stiles above and below the pivots.

3. In a device of the character described, a sheet-metal frame having side casings with sash-bearings, a sash pivoted to the side casings, a pair of flanges on the bearing-surface of the sash-stiles, a shoulder along each edge of the sash-bearings, one of the flanges of each sash-stile being bent over above the pivot and the other of said flanges being bent over beneath the pivot, the remaining outstanding portions of said flanges engaging with the shoulders of the sash-bearings, a cross-rail connecting the side casings and against which the sash fits, metal strips provided with double flanges secured to the sash-bearings below the cross-rail and a window-light secured in the flanges of the metal strips.

4. In a device of the character described, a

sheet-metal frame, a tubular sash, a pivotal connection between the sash and frame comprising a socket-plate, a slotted plate, a pivot-pin having one end turnable in the socket of the socket-plate, arms on the pivot-pin capable of passing through the slot of the slotted plate and engaging said plate when turned, and a nut threaded on the other end of the pivot-pin to coact with the arms and clamp the pivot-pin in its adjusted positions in the slot of the slotted plate.

5. In a device of the character described, a sheet-metal frame, a tubular sash, pivotal connections between the sash and frame comprising a socket-plate, a slotted plate, back plates secured within the frame and sash respectively to which the socket-plate and slotted plate are secured, a pivot-pin having one end turnable in the socket of the socket-plate, arms on the pivot-pin capable of passing through the slot of the slotted plate and engaging said plate when turned, and a nut threaded on the other end of the pivot-pin to coact with the arms and clamp the pivot-pin in its adjusted positions in the slot of the slotted plate.

6. In a device of the character described, a tubular sheet-metal frame comprising cored side casings provided with projecting sash-bearings and shoulders at the edges of the sash-bearings, a cored top casing having an inclined flanged sash-stop, a cored sill provided with a flanged glass-seat, a cross-bar provided with a shouldered glass-seat and an inclined flanged sash-stop, a tubular sash, a socket-plate secured to each side casing, an angular plate secured to each side stile of the sash and provided with a slot, pivot-pins adjustable in the slots of the angle-plates and journaled in the socket-plates, said sash-stiles having a pair of flanges, one of said flanges being bent over above the pivots and the other of said flanges being bent over beneath the pivots and the unbent portions of said flanges adapted to engage the shoulders of the sash-bearings, inclined flanged top and bottom bars on the sash to make weather-tight joints with the sash-stops, and window-lights in the sash and in the glass-seats.

7. In a device of the character described, a tubular sheet-metal frame comprising cored side casings provided with projecting sash-bearings, a cored top casing having an inclined flanged sash-stop, a cored sill provided with a flanged glass-seat, a cross-bar provided with a shouldered glass-seat and an inclined flanged sash-stop, a tubular sash, a socket-plate secured to each side casing, a plate secured to each side stile of the sash and provided with a slot, pivot-pins adjustable in said slots and journaled in the socket-plates, inclined flanged top and bottom bars on the sash to make weather-tight joints with the sash-stops, and window-lights in the sash and in the glass-seats.

8. In a device of the character described, a

glass-cleat comprising a piece of sheet metal folded at its intermediate portion with its edges bent away from each other to form a T shape in cross-section, one of said edges being adapted to be placed between the glass and the glass-seat so that the other edge thereof bears upon the glass-seat outside of the glass and the doubled portion bears on the glass. 70

9. In a device of the character described, a glass-cleat comprising a piece of sheet metal folded at its intermediate portion with its edges bent away from each other, to form a T shape in cross-section with one edge slightly out of alinement with the other, one of said edges being adapted to be placed between the glass and the glass-seat so that the other edge thereof bears upon the glass-seat outside of the glass and the doubled portion bears on the glass. 75 80

10. In a device of the character described, a sheet-metal frame having a side casing with a sash-bearing, a U-shaped strip of metal adapted to fit upon and embrace the sash-bearing of the side casing and having bent in the middle portion a pair of parallel glass-holding flanges, 90 and a window-light held between said flanges. 85

11. In a device of the character described, a frame having sash-bearings with opposite shoulders, a sash pivoted to the frame, and a pair of parallel flanges formed on the bearing-surface of the sash-stiles at a distance apart to fittingly embrace between them the shoulders of the sash-bearings on the frame, one flange on each sash-stile being bent over to clear the shoulder of the sash-bearing above the pivot and the other flange being bent over to clear the shoulder of the sash-bearing below the pivot, the remaining outstanding portions of the flanges forming inside and outside stops with the shoulders of the sash-bearing 100 above and below the pivots. 105

12. In a device of the character described, a frame having sash-bearings with opposite shoulders, a sash pivoted to the frame, and a pair of parallel flanges formed on the bearing-surface of the sash-stiles at a distance apart to fittingly embrace between them the shoulders of the sash-bearings on the frame, one flange on each sash-stile being bent over between the sash-stile and the sash-bearing to fit against the sash-bearing above the pivot and the other flange being bent over between the sash-stile and the sash-bearing to fit against the sash-bearing below the pivot, the remaining outstanding portions of the flanges forming inside and outside stops with the shoulders of the sash-bearing above and below the pivots. 110 115 120

13. In a device of the character described, a frame having sash-bearings with opposite shoulders, and a sash pivoted to the frame, the stiles of the sash being formed of a sheet-metal shell with a bearing-plate held between its front and rear plates which are bent over the edges of the bearing-plate to form slip- 125 130

joints therewith and produce a pair of parallel flanges along the bearing edge of each sash-stile in the same planes as the front and rear plates thereof, the parallel flanges being at 5 such a distance apart as to fittingly embrace between them the shoulders of the sash-bearing on the frame, one of the flanges of each sash-stile being bent over between the sash-stile and the sash-bearing to fit against the 10 sash-bearing above the pivot and the other flange being bent over between the sash-stile

and the sash-bearing to fit against the sash-bearing beneath the pivot, the remaining outstanding portions of the flanges forming inside and outside stops with the shoulders of 1 the sash-bearing above and below the pivots.

In testimony whereof I affix my signature in presence of two witnesses.

JOHN BOGENBERGER.
